UNITED STATES PATENT OFFICE.

LEONARD D. SHRYOCK, OF MARIETTA, OHIO.

WELL-DRILLING MACHINE.

SPECIFICATION forming part of Letters Patent No. 783,227, dated February 21, 1905.

Application filed May 24, 1904. Serial No. 209,436.

To all whom it may concern:

Be it known that I, LEONARD D. SHRYOCK, a citizen of the United States, residing at Marietta, in the county of Washington and State 5 of Ohio, have invented certain new and useful Improvements in Well-Drilling Machines, of which the following is a specification, reference being had therein to the accompanying drawings.

10 This invention relates to well-drilling machines, and more particularly to an improvement in the apparatus shown in my application for Letters Patent filed December 15, 1903, Serial No. 185,212.

15 The invention has reference to the spudding mechanism; and it consists primarily of an oscillating sheave-carrying support adapted, preferably, to be actuated by the spudding-line shown in my above-recited application for 20 imparting the necessary movement to the drilling-cable.

In the accompanying drawings, Figure 1 is a side elevation of a drilling-machine equipped 25 with the improvement. Fig. 2 is a top plan view of the same. Fig. 3 is a rear end view of the machine-frame and a portion of the spudding mechanism. Fig. 4 is a detail view.

30 As the structural details and operation of the drilling-machine are fully described in my above-recited application, the present description will be confined to the improvement herein claimed and the parts of the apparatus immediately associated therewith.

Referring to the drawings, 2 designates the 35 machine-frame, and 3 the main shaft journaled therein, having at one end crank 4 and at its opposite end band-wheel 5, which is driven by belt 6 from engine 7. Journaled on the frame at the rear of crank 4 and at an angle thereto 40 is sheave 8, over which passes spudding-line 9. Sheave 8 is so disposed as to direct the line in the plane of movement of wrist 4' of the crank, one end of the line being connected thereto, while its main portion extends forward 45 in a diagonal direction and operatively connects with the drilling-cable. In my former application this connection is made by means of an ordinary shoe which embraces the cable. This arrangement is objectionable, as there is

no provision other than the tension of line 9 5c for preventing vertical displacement of the shoe, and, furthermore, the cable is subjected to considerable wear on account of the frictional engagement therewith. In the present invention these difficulties are obviated by 55 connecting the forward end of line 9 to an upright arm 11, which at its lower end is secured to or mounted on the short shaft 12 in frame 2 and is thus adapted to oscillate longitudinally of the machine-frame. Arm 11 is forked at its 60 upper end and carries sheave 13 over which drilling-cable 10 passes as it comes from reel 14 and ascends from anchor-pulley 15 to crown-pulley 16. The spudding-line 9 is detachably connected to arm 11, preferably by 65 means of a clevis 17, formed with hook extremities 17', which engage eyes 18 of arm 11 at opposite sides of sheave 13. A rope 19 may be connected with arm 11 and extend downward through pulley 20, secured to mast 70 21, by means of which the arm may be conveniently held in operative position for connecting the spudding-line thereto.

With the sheave-carrying arm proposed by the present invention there is absolutely no 75 wear on the drilling-cable as it is deflected in the operation of spudding, and it is impossible for the spudding-line connection to shift vertically, an objection incident to my prior construction. Hence the successive deflections of the drilling-cable are uniform, and the same is necessarily true of the working strokes 80 of the tools.

I claim—

1. A drilling-machine comprising a frame, 85 an arm mounted to oscillate in the frame and adapted to operatively engage and deflect the drilling-cable, a shaft having a crank, a sheave intersecting the plane of rotation of the crank and arranged at an angle thereto, and a spudding-line passing over the sheave and connected at one end to the crank and at its opposite end to said arm.

2. A drilling-machine comprising a frame, 95 an arm mounted to oscillate therein, said arm having a forked free end, a sheave journaled in the fork and adapted to engage and deflect the drilling-cable, a reciprocating spudding-

line, and a clevis carried by the line adapted to engage the forked extremity of said arm.

3. A drilling-machine comprising a frame, an upright arm mounted to oscillate therein, the upper end of the arm being forked, a sheave journaled in the fork and adapted to engage and deflect the drilling-cable, eyes carried by the arm-forks, a reciprocating spud-

ding-line, and a clevis at the extremity of the line formed with hooks to engage said eyes. 10

In testimony whereof I affix my signature in presence of two witnesses.

LEONARD D. SHRYOCK.
